UNITED STATES PATENT OFFICE.

ALBERT OBERHEIM, OF OGDEN, UTAH.

DISH-WASHING MACHINE.

1,127,801.

Specification of Letters Patent. Patented Feb. 9, 1915.

Application filed May 24, 1913. Serial No. 769,681.

To all whom it may concern:

Be it known that I, ALBERT OBERHEIM, a citizen of the United States, residing at Ogden, in the county of Weber and State of Utah, have invented certain new and useful Improvements in Dish-Washing Machines, of which the following is a specification.

This invention relates to improvements in machines which are employed in detergent purposes and more particularly to machines of that class which are used for washing or cleansing dishes or the like.

An object of this invention is the provision of baskets for holding the dishes which will permit of a thorough washing of them and further insure against the chipping or breaking during the washing operation.

Another object of this invention is the provision of a receptacle or tank which is divided into two separate compartments, one for the washing and one for the cleansing of the dishes and also the provision of a drain board alongside of the cleansing tank upon which the dishes may be placed for drainage, prior to the drying thereof.

With the foregoing and other objects in view, this invention consists in such novel features of construction, combination and arrangement of parts as will be hereinafter more fully described, illustrated in the accompanying drawings and claimed.

In describing the invention in detail, reference will be had to the accompanying drawings wherein like characters of reference designate like or corresponding parts throughout the several views, and in which,

Figure 1 is a perspective view of the improved dish-washing machine; Fig. 2 is a sectional view through the device; Fig. 3 is a top plan view of a basket or receptacle used for holding such dishes as plates, saucers or the like; Fig. 4 is a top plan view of a basket or receptacle for holding cups or other dishes of similar shape; Fig. 5 is an end view of Fig. 3; Fig. 6 is an end view of Fig. 4; and Fig. 7 is a detail view of one form of means for starting the motor.

Referring more particularly to the drawings, 1 designates a receptacle or tank which is constructed with fluid-tight joints and which has a partition 2 centrally disposed therein, and dividing the interior of the same into two separate compartments 3 and 4.

The compartment 3 is provided for the

washing of the dishes and has an agitating means, in the form of an ordinary rotary propeller 5 disposed therein adjacent one end. The propeller 5 is mounted upon the shaft 6 which extends through the end 7 of the tank 1 and has a bevel gear 8 mounted upon the end thereof which extends into a compartment 9 which is formed adjacent one end of the tank 1. The compartment 9 has its upper end closed by a movable covering 10. A second bevel gear 11 meshes with the bevel gear 8 and is mounted upon a vertical shaft 12 which has a bevel gear 13 mounted upon its upper end. The bevel gear 13 meshes with a bevel gear 14 which is mounted upon a shaft 15. The shaft 15 is carried by any suitable power producing means 16, such as a water turbine, an electric motor or other similar power-producing means. The shaft 12 is supported by a bracket 17 which is secured to one end of the tank 1 while the power producing means 16 is mounted upon a bracket 18 which is also secured to the end of the tank 1 and extends into the compartment 9.

The compartment 3 has a foraminated plate 20 mounted therein, which plate is pivotally connected to one side of the tank 1 and to the partition 2 as at 21 and has connected to its free end 22 a pair of rods 23 which extend upwardly within the interior of the compartment 3 and are connected to a rod 24 which extends laterally across the compartment 3 near the upper edge of the same and which is connected to a rod 25. The rod 25 extends through an opening 26 formed in the end of the compartment 3 and extends into the compartment 9 being connected to means for controlling the operation of the power-producing means 16. By connecting the foraminated plate 20 to the rods 23 and 25 the operation of the power-producing means 16 may be controlled by the forcing downwardly of the end 22 thereof as when a basket full of dishes is placed thereupon, causing the power-producing means 16 to start and impart rotary motion to the propeller 5 for agitating the water or other liquid contained within the compartment 3. A coil spring 26 is disposed between the end 22 of the plate 20 and the upper side of the bottom of the compartment 3 and tends to hold the plate 20 in an upward position as is shown in Fig. 2 of the drawings, when there is no weight there-

- upon. The compartment 4 which is provided for the cleansing or rinsing of the dishes after the same have been washed also has a foraminated plate, an agitator and means for connecting the plate to the power-producing means 16 mounted therein as has the compartment 3.
- Each of the compartments 3 and 4 has an outlet pipe 27 communicating with the lower end thereof which pipes are controlled by a valve 28 which is mounted therein.
- The compartment 3 has a table 29 formed adjacent thereto and which table has its outer edge supported by lugs 30 and is provided with an opening 31, which opening has a pipe 32 extending downwardly therefrom. The opening 31 and the pipe 32 are provided for disposing of the refuse which is left upon the dishes which is forced downwardly through the pipe 32 into the garbage receptacle or can 33 which is placed directly beneath the lower end of the pipe 32. The table 29 forms what is commonly known as a scraping board.
- A draining or drying board 34 which is similar in construction to the table 29 is mounted adjacent the compartment 4 of the tank 1 and has its outer edge supported by means of legs 35. The upper surface of the draining board 34 is provided with a plurality of grooves 36 which extend laterally thereacross and provide a means for the water which drains off the dishes to run back into the compartment 4.
- For the purpose of maintaining the liquids which are contained in the two compartments 3 and 4 at a desired temperature, a steam or other heating pipe 37 enters the compartments and passes entirely about them the same being controlled by a valve 38 which is disposed upon the exterior of the tank 1.
- In Figs. 3 and 5 of the drawings a basket or foraminated receptacle 40 is shown, the same being divided into a plurality of separate angularly arranged compartments 41 which are provided for the reception of plates, saucers or dishes of similar construction and which keep each plate or dish separate and from contacting with one another whereby the dishes will be prevented from chipping or breaking and as the partitions 42 which form the compartments 41 are also foraminated water can pass freely therethrough and allow the dishes to be thoroughly and efficiently washed and rinsed. The foraminated receptacle or basket 40 has a handle 43 connected thereto so that the same may be easily placed within either of the compartments 2 or 3 and removed therefrom.

In Figs. 4 and 6 of the drawings a basket or foraminated receptacle 45 is shown which is similar in construction to the basket 40, but which has a plurality of various com-

partments 46 arranged laterally within the interior of the basket and shaped so as to efficiently engage and hold rigidly cups or dishes similar in construction thereto. Each of the partitions 47 which form the compartments 46 has a plurality of circular-shaped openings 48 formed therein as is clearly shown in Fig. 6 of the drawings. These circular openings form the means for supporting the cups or similarly shaped dishes.

In practical fields, certain minor features of construction, combination and arrangement of parts may necessitate alterations to which the patentee is entitled, provided such alterations are comprehended within the scope of what is claimed.

What is claimed is:—

1. In a detergent machine, a tank, a vertically movable support within said tank, an agitator, a prime mover in geared connection with said agitator, and means actuated by movement of the support under the weight of the article to be cleansed for starting said prime mover.
2. In a detergent machine, a tank, a resiliently mounted and vertically movable support within said tank, an agitator, a prime mover in geared connection with said agitator, and means actuated by the movement of said support downwardly or upwardly for starting or stopping said prime mover.
3. In a detergent machine, the combination of, a tank, a foraminous support within said tank, said support having one end horizontally pivoted to said tank, an agitator, means of propulsion for said agitator, a rod pivotally connected to the free end of said support, a second rod connected to said first named rod and controlling the operation of said propulsion means in such a manner that said agitator will be thrown into operation when the object to be cleansed is placed upon said support, resilient means disposed beneath the support for causing the support to assume its normal position and operate said connection for throwing said agitator out of operation when the article to be cleansed is removed from said support.
4. In a dish washing machine, a body portion, a horizontally pivoted receptacle support within said body portion, an agitator mounted within said body portion, means for operating said agitator and means actuated by the movement of the support under the weight of an article to be cleansed for starting said operating means.
5. In a detergent machine, a tank, a vertically movable support within said tank, an agitator, a prime mover in geared connection with said agitator, means actuated by displacement of the support under the weight of an article to be cleansed for starting said prime mover, and means for auto-

matically replacing said support for reactuating said first named means to stop said prime mover when the support is relieved of the weight of the article to be cleansed.

5. 6. In a detergent machine, a tank, a support in said tank having one end horizontally pivoted thereon, an agitator, a prime mover in geared connection with said agitator, means actuated by movement of the
10 support under the weight of the article to be cleansed for starting said prime mover, springs connected to the free end of said

support for causing the support to assume its normal position and reactuate said means for throwing said agitator out of operation 15 when the article to be cleansed is removed from said support.

In testimony whereof I affix my signature in presence of two witnesses:

ALBERT OBERHEIM.

Witnesses:
